(57) **CLAIM**

The ornamental design for an interactive electronic card with display and button, as shown and described.

DESCRIPTION

FIG. 1 is a front, bottom, and left side perspective view of our new design for an interactive electronic card with display and button;

FIG. 2 is a back, top, and left side perspective view thereof;

FIG. 3 is a front side view thereof;

FIG. 4 is a back side view thereof;

FIG. 5 is a top side view thereof;

FIG. 6 is a bottom side view thereof;

FIG. 7 is a left side view thereof; and,

FIG. 8 is a right side view thereof.

The broken lines showing environment in the drawings are for illustrative purposes only and form no part of the claimed design.

1 Claim, 5 Drawing Sheets
